UNITED STATES PATENT OFFICE.

GEORGE F. WOLFE, OF ROCHESTER, NEW YORK, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

ROUGH-ROUNDING AND CHANNELING MACHINE.

No. 804,645.

Specification of Letters Patent.

Patented Nov. 14, 1905.

Application filed March 31, 1902. Serial No. 100,735.

To all whom it may concern:

Be it known that I, GEORGE F. WOLFE, a citizen of the United States, residing at Rochester, in the county of Monroe and State of New York, have invented certain new and useful Improvements in Rough-Rounding and Channeling Machines; and I do hereby declare the following to be a full, clear, and exact description of the invention, such as will enable others skilled in the art to which it appertains to make and use the same.

The present invention relates to an improvement in rough-rounding and channeling machines.

The object of the present invention is to re-organize and improve machines of the above class by providing such machines with a grooving-knife and mechanism whereby the channeling-knife may be thrown out of operation during any part of the operation upon a shoe-sole and the grooving-knife may be thrown into operation and, conversely, so that the grooving-knife may be thrown out of operation and the channeling-knife again thrown into operation.

My invention is particularly adapted for use in operating upon shoe-soles that are stitched aloft, and while I am aware that it has been proposed to provide a rough-rounding and channeling machine with a channeling-knife which can be thrown out of and into operation during the continued operation of the machine my invention contemplates the employment in connection with a device of that character of means for throwing the grooving-knife into and out of operation, so that the stitching aloft may lie in a shallow groove in the bottom of the sole, with the advantages well known to those skilled in the art.

A further object of my invention is to improve rough-rounding and channeling machines in other respects hereinafter pointed out.

To the above end the present invention consists in the devices and combinations of devices hereinafter described, and particularly defined in the claims.

In the accompanying drawings, illustrating the preferred form of my invention, Figure 1 is a sectional elevation of a portion of the rough-rounding and channeling machines illustrated and described in Letters Patent of

the United States granted to French and Meyer, February 22, 1898, No. 599,602, and March 22, 1898, No. 600,883, only so much of 55 the machine of said patents being shown as is necessary for an explanation of my invention, reference being had to said patents for a disclosure of a machine with which the specific embodiment of my invention is particularly 60 designed to coöperate. Fig. 2 is a plan of the parts shown in Fig. 1. Fig. 3 is a plan, Fig. 4 a front elevation, and Fig. 5 an end elevation, of the channeling-knife and its carrier. Fig. 6 is a side elevation. Fig. 7 is a bottom 65 plan of the slide for operating the grooving-knife; and Fig. 8 is a plan, and Fig. 9 a side elevation, of the grooving-knife and its carrier.

The channeling-knife 1 is mounted in a 70 suitable carrier, (indicated in a general way by the reference character 2,) which is slidably mounted in a vertically-movable knife-carrier support 3. The grooving-knife 4 is mounted in a grooving-knife carrier 3, also slidably 75 mounted in the knife-carrier support 3. The sole-rest 6 is revolubly mounted upon the knife-carrier support 3, which is carried by the carrier-block 7, carried in the usual way by the oscillating pivoted arm 8 of the machine of said patents. The knife-carrier support 3, the sole-rest 6, the sliding block 7, and the oscillating arm 8 are the same, except as hereinafter described, as in the machine of 80 said patents.

The channeling-knife 1 is provided with a dovetailed shank 9, which is received in a correspondingly-shaped groove formed between the clip 10 and the body of the carrier 11, being secured therein by means of the 85 screw 12. The channeling-knife carrier 2 is provided with a dovetailed projection 13, which is received by a correspondingly-shaped recess in a projection 14 from the top of the knife-carrier support 3, extended rearwardly 90 toward the left in a diagonal direction looking at the machine from the front. The upper side of the channeling-knife carrier 2 is provided with a pin 15, adapted to coöperate with a groove in the operating-lever herein- 95 after referred to. The above-described arrangement is such that the channeling-knife carrier may be moved by its operating-lever from its operative position, as shown in Figs.

1 and 2, rearwardly along a path oblique to the line of cut—that is to say, in the diagonal direction away from the sole of a shoe—so that it shall cease to cut a channel therein.

- 5 The grooving-knife 4 is provided with the dovetailed shank 16, which is received in a correspondingly-shaped groove in the grooving-knife carrier 5, being secured in proper position therein by means of the set-screw 17.
- 10 The grooving-knife carrier 5 is received in a correspondingly-shaped hole 18 in the top of the knife-carrier support 3 and is adapted to reciprocate in said hole toward and from the front of the machine. Means are provided
- 15 for moving the grooving-knife forward when the channeling-knife is withdrawn from operative position and for moving the grooving-knife backward when the channeling-knife is moved forward into operative position.
- 20 Such means in the illustrated embodiment of my invention consists of a slide 19, provided on its under side with a diagonal slot 20, which engages a pin 21, projected upwardly from the upper side of the shank of the grooving-knife carrier 5. The reciprocations of the
- 25 slide 19 impart corresponding reciprocations to the grooving-knife. The slide 19 is received in a slot 22, arranged at right angles to the hole 18, in which slot it is held by means of the plate 23, secured to the knife-carrier support 3 by means of screws. The slide 19 is provided upon its rear end with a pin 24, which is adapted to engage with the operating-lever hereinbefore referred to and which
- 30 will presently be described.

It is to be noted that the channeling-knife and grooving-knife move in paths inclined to and intersecting each other and that their operative positions are substantially the same

- 40 with relation to the sole-rest, projecting slightly beyond the surface of the sole-rest and at one end of the same.

Means are provided for retracting the channeling-knife and projecting the grooving-knife, which means also operate to retract the grooving-knife and project the channeling-knife. Such means in the illustrated embodiment of my invention consists of a lever 25, pivoted at 26 upon the projection 14 from the knife-carrier support 3. The lever 25 is provided with a slot 27, adapted to receive the pin 15, projecting upwardly from the upper side of the channeling-knife carrier, hereinbefore referred to. When the lever 25 is turned about its pivot 26, the channeling-knife carrier will be moved thereby either to retract the channeling-knife from its operative position or to project the same forward into operative position. The lever 25 is also provided with a cam-slot 28, which receives the pin 21, projected upwardly from the upper side of the slide 19, which actuates the grooving-knife carrier. Inasmuch as the channeling-knife and the grooving-knife occupy substantially the same place when they

are in their operative positions, the channeling-knife must first be withdrawn from operative position before the grooving-knife can be projected forward. The first part of the movement of the lever 25 must operate, therefore, to withdraw the channeling-knife from operative position. The slot 28 is therefore provided with an idle portion formed upon a curve of which the pivot of the lever 25 is the center, so that this portion of the movement of the lever 25 is without effect upon the grooving-knife. As soon, however, as the channeling-knife has been retracted a short distance the grooving-knife may begin its forward movement, and in order to make this movement as rapid as possible the steep portion in the slot 28 is provided, which, engaging the pin 24, rapidly retracts the slide 19, said slide 19 operating by means of its groove 20 upon the pin 21 in the grooving-knife carrier to project the same forward into operative position. In order that the grooving-knife may be held forward in its operative position, the slot 28 is provided with a further idle portion upon the opposite side of the steep portion above referred to, so that after the lever 25 has been turned so that the pin 24 occupies the right-hand end of the slide 28, as seen in Fig. 2, the slide 19 will be held from movement by said slot, and consequently the grooving-knife 4 will be securely held in operative position. During the latter part of the motion of the lever 25 the retracting movement of the channeling-knife will be completed. A stop-pin 29, projected through the lever 25, engages a correspondingly-shaped hole in the projection 14 when the channeling-knife is forward in its operative position, so as to hold the lever stationary, thereby in turn holding the channeling-knife stationary in its operative position against the thrust of the knife during its cutting stroke. The stop-pin 29 is secured to the end of an auxiliary lever 30, pivoted at 31 upon the lever 25, so that the operator may grasp the two levers 25 and 30 between the fingers and by pressing them together against the action of the spring 32, which normally supports the lever 30 and tends to force the stop-pin 29 downward, so that it may engage its hole in the projection 14, he may lift the stop-pin out of its hole, thereby releasing the lever 25, whereupon he will push the lever rearwardly, whereby first the channeling-knife will begin to be withdrawn from its operative position and thereafter the grooving-knife will be moved forward into operative position and locked in such position. In order to withdraw the grooving-knife from operative position and to throw the channeling-knife into operative position, the operator will pull the lever 25 forwardly, thereby first withdrawing the grooving-knife from operative position and then forcing the channeling-knife into operative position.

Then the stop-pin 29 will drop into its hole and the parts will be locked in the position shown in Figs. 1 and 2.

While I have described my invention in connection with the rough-rounding and channeling machine illustrated in the aforesaid patents, I do not intend to limit my invention to such specific embodiment, as the same may be embodied in other forms without departure therefrom.

Having thus described my invention, I claim as new and desire to secure by Letters Patent of the United States—

1. A rough-rounding and channeling machine, having, in combination, a channeling-knife, a grooving-knife, and means for throwing one of the knives out of operation and the other knife into operation, said knives having the same operative position, substantially as described.

2. A rough-rounding and channeling machine, having, in combination, a channeling-knife, a diagonally-arranged sliding carrier, upon which said channeling-knife is mounted, a grooving-knife, a sliding carrier upon which said grooving-knife is mounted, and means for operating the channeling-knife and grooving-knife carriers to throw one knife into operation and the other knife out of operation, substantially as described.

3. A rough-rounding and channeling machine, having, in combination, a channeling-knife, a channeling-knife carrier, a grooving-knife, a grooving-knife carrier, a lever for operating said carriers provided with two slots, one for operating the channeling-knife carrier and the other for operating the grooving-knife carrier and means connected with said carriers engaging said slots, substantially as described.

4. A rough-rounding and channeling machine, having, in combination, a channeling-knife, a channeling-knife carrier, a grooving-knife, a grooving-knife carrier, a knife-carrier support provided with guideways for the knife-carriers inclined with relation to each other, and located in substantially the same plane, and means for actuating the knife-carriers, substantially as described.

5. A rough-rounding and channeling machine, having, in combination, a channeling-knife, a channeling-knife carrier, a grooving-knife, a grooving-knife carrier, a knife-carrier support, a sole-rest mounted on said knife-carrier support, said knife-carrier support being provided with guideways for the knife-carriers inclined with relation to each other so that the knives in operative position project slightly beyond the surface of the sole-rest and at one end of the same, and means for actuating the knife-carriers, substantially as described.

6. A rough-rounding and channeling machine, having, in combination, a channeling-knife, a grooving-knife, means for support-

ing the knives so that they are movable along intersecting paths, and a lever for actuating the knives provided with a stop to hold said lever stationary with the channeling-knife in operative position, substantially as described. 70

7. A rough-rounding and channeling machine, having, in combination, a channeling-knife, a grooving-knife, carriers for the knives, and a lever for actuating both carriers to move the one out of and the other into operative position, substantially as described. 75

8. A rough-rounding and channeling machine, having, in combination, a channeling-knife, a grooving-knife, carriers for the knives, means for actuating the knives comprising a lever provided with a stop to hold the channeling-knife in operative position, and with a surface to hold the grooving-knife in operative position, substantially as described. 80

9. A rough-rounding and channeling machine, having, in combination, a channeling-knife, a grooving-knife, carriers for the knives, and means for moving the carriers having provision for holding either the one or the other of the knives in the same operative position, substantially as described. 85

10. A rough-rounding and channeling machine, having, in combination, channeling and grooving knives movable along intersecting paths, and means for actuating the knives to throw one into and the other out of operative position, substantially as described. 90

11. A rough-rounding and channeling machine, having, in combination, channeling and grooving knives, a sole-rest and means for moving either the one or the other of the knives into substantially the same position with relation to the sole-rest, substantially as described. 100

12. A rough-rounding and channeling machine, having, in combination, a channeling-knife, a grooving-knife, and means for moving either the one or the other of the knives into the same operative position, substantially as described. 105

13. A rough-rounding and channeling machine, having, in combination, a channeling-knife, a grooving-knife, carriers for the knives, and connected means for moving both of the carriers having provision for holding either the one or the other of the knives in the same operative position, substantially as described. 110

14. In a machine for preparing the outsoles of boots and shoes for attachment to lasted uppers and insoles, the combination with a channeling-knife and a grooving-knife, of means under the control of the operator whereby either of the said knives may be brought into and moved out of operative position without stopping the machine or breaking the continuity of operation of said knives, to form a channel in a portion of the shoe-sole and a continued stitch-receiving groove, and means to operate said knives, substantially as described. 115

15. In a machine for preparing the outsoles 120

- of boots and shoes for attachment to lasted uppers and insoles, the combination with a channeling-knife and a grooving-knife, of means under the control of the operator where-
5 by either of the said knives may be brought into and moved out of operative position without stopping the machine or breaking the continuity of operation of said knives, to form a channel in a portion of the shoe-sole and a con-
tinued stitch-receiving groove and means to
10 vibrate said knives, substantially as described.
16. In a machine for preparing the outsoles of boots and shoes for attachment to lasted uppers and insoles, the combination with a

grooving-knife and a channeling-knife, means 15 under the control of the operator for alternately advancing and retracting said knives to and from operative position to cause one of said knives to continue the line of cut made by the other of said knives and means for im-
parting to said knives their cutting move-
ments, substantially as described.

In testimony whereof I affix my signature in presence of two witnesses.

GEO. F. WOLFE.
